UNITED STATES PATENT OFFICE.

BENJAMIN S. HARBACH, OF PHILADELPHIA, PENNSYLVANIA.

METHOD OF AMALGAMATING.

SPECIFICATION forming part of Letters Patent No. 340,504, dated April 20, 1886.

Application filed August 3, 1885. Serial No. 173,411. (No model.)

To all whom it may concern:

Be it known that I, BENJAMIN S. HARBACH, a citizen of the United States, residing at Philadelphia, in the county of Philadelphia, and 5 State of Pennsylvania, have invented certain new and useful Improvements in Methods of Amalgamating, of which the following is a specification, reference being had therein to the accompanying drawings.

10 The object of this invention is to effect a rapid and economical separation of gold from the earth in which it is found without the use of water; and to this end the invention consists in a new method for accomplishing what is 15 generally known as "dry amalgamation," the details of which will be hereinafter fully explained.

Figure 1 is a vertical section on line *y*, *y*, Fig. 2. Fig. 2 is an end elevation. Fig. 3 is a 20 transverse section on line *x*, *x*; Fig. 1. Fig. 4 is a side elevation. Fig. 5 is a detached view, enlarged, of one of the spirals or convolutions of the conveyer.

Like figures indicate like parts in all the 25 views.

1 1 are the posts, 2 2 the sills, and 3 a cross-girt, of the frame, which, however, may be of any construction adapted to support the operative parts of my machine.

30 4 is a cylinder-head at the head end or receiving end of the machine.

5 6 is the lower half of the cylinder or casing, which is semicircular in cross-section and of uniform diameter throughout, except that 35 at its rear end or discharging end it is contracted, as at 6, (see Figs. 1, 2, 4,) whereby the lower side at its extreme rear end is somewhat elevated, for a purpose which will be explained. I prefer to use a second semi-cylinder or shell, 7, which may be hinged to the 40 part 5 6, as at 8 8.

9 is a half-head closing the discharging end of the machine above the girt 3.

10 is a shaft mounted in suitable bearings 45 on the frame-work—for instance, as indicated in the drawings—and provided at suitable intervals with spider-arms 11 11, the hubs of which are keyed or otherwise made fast to the shaft.

50 12 represents the convolutions of a conveyer or worm mounted upon and carried by the

spider-arms, and of an external diameter a little less than the internal diameter of the shell, so as to revolve in close proximity to said shell.

13 14 are spider-arms and convolutions at the tail end of the conveyer, and are of such reduced diameter as will correspond substantially to the reduced size of the part 6 of the casing.

15 16 is a trough arranged below the shell, which latter is cut away to correspond with the upper edges of the sides of the trough. By preference the bottom of this trough is inclined, as indicated in Fig. 1.

17 is a feed-hopper, through which the mingled mass of gold, earth, and other materials may be fed into the machine. There may be a supply-pipe opening into the head end of the trough, as at 18, Fig. 1.

19 20 represent, respectively, a discharge-pipe and stop-cock or other gate located at the tail end of the trough, through which to draw off its contents, as may be desired.

21 is a transverse partition placed in the 75 trough near the discharging end of the machine, the lower edge of the partition being a short distance above the bottom of the trough, so as to form a throat through which the contents of the trough may pass.

22 is a pulley or band wheel on the end of shaft 10. This pulley may be belted to any convenient motor.

23 23 are holes—one or more—in the widened rear ends, 16, of the trough, to permit the passage of air and the overflow of mercury, as will be explained.

24 is a bracket or saddle, in which the head end or receiving end of the shell 5 6 may be conveniently supported.

I do not wish to be limited to the particular form of conveyer-spirals shown, nor to arranging them at any particular inclination or pitch, nor to making them in a substantially continuous worm or thread, as is indicated, 95 because, under some circumstances, I may find it desirable to use separate convolutions, substantially as indicated in Fig. 5.

By an examination of the drawings it will be seen that when the trough is filled with 100 quicksilver its upper surface will be a little above the lower edges of the conveyer-blades,

- so that during the revolutions of the conveyer the mingled mass of gold, auriferous earth, and other material will be rolled, tumbled, and thoroughly agitated in such manner that 5 all portions of it will be successively brought into contact with the quicksilver, and that the gold will sink to the bottom of the trough, or at least into the quicksilver; but the refuse will be slowly advanced over the surface of 10 the quicksilver, and finally discharged at the rear end of the machine without seriously disturbing the surface of the quicksilver, or, under ordinary circumstances, causing it to bank up in advance of the conveyer-blades.
- 15 In order to effectually guard against the quicksilver being advanced from the head machine toward the discharging end, I have extended both sides of the trough beyond the lines at which it (the trough) is intersected by 20 the shell or cylinder, into which extensions the quicksilver and such gold as may be accumulated therein can flow temporarily.

The inclined reduced portion 6 of the cylinder, while it will not interfere with the discharge of refuse, will return to the trough any quicksilver which may possibly be carried thither with the refuse and would otherwise be discharged and wasted.

In order to guard against any loss or wastage by reason of the quicksilver or gold adhering to the conveyer, I make it wholly of iron or other neutral material, whereby I am enabled to accomplish a satisfactory separation of the gold from the earth and other impurities in a more economical manner than has ever before been attained.

As a further safeguard against the contents of the trough being forced rearward and out of the machine with the refuse, I provide the 40 partition 21, the upper edge of which is on a line with the lower line of the conveyer, the lower edge of the partition being a short distance from the bottom of the trough, and through the throat thus formed the quicksilver and portions of all of the gold in the trough 45 will pass when the stop-cock 20 is opened.

By slowly introducing a fresh supply of mercury at 18, and leaving the stop-cock slightly open, a continuous flow of mercury and gold 50 through the trough can be maintained, and the mercury, after the gold has been separated therefrom, may be returned and run through the machine again.

Should the mercury from any cause—such 55 as accumulation of gold in the trough—rise above its sides into the cylinder, it would not, under ordinary circumstances, rise high enough to be discharged at the tail end with the refuse, because of the overflow-holes 23, (see Figs. 1 60 and 4,) thus avoiding the waste of quicksilver and gold which might otherwise result.

Although I regard iron as the best material for the conveyer, yet I do not wish to be limited thereby, because I may use any other material which is neutral—that is to say, to which 65 quicksilver will not adhere when brought into

contact therewith by the operation of the machine.

Of course a hand crank may be used instead of a band-wheel to drive the conveyer.

I am aware of the fact that use has been made of rectilinearly-moving brushes to carry dry material over mercury, said brushes being arranged perpendicularly to their path; but I so treat the material that it shall be turned 75 and tumbled over and over, and the mercury is not pushed directly forward as it is by devices similar to the brushes above mentioned. No disturbance of the mercury is caused by the conveyer blades, the latter in my construction differing from those conveyers heretofore used in their arrangement relatively to the mercury and the walls which retain the pulp. A slow forward movement of the amalgamated material in the trough is facilitated by having 80 the body of mercury gradually increase in depth, so that the heavier portion cannot reach the bottom at once, but shall be suspended more or less until it reaches the exit. By so arranging the parts that they shall act 85 in this way I can supply at the upper end fresh mercury, which shall be substantially proportional to the valuable material delivered to its surface, and which can be caused to move as a current, either continuously or at 90 such intervals as are advantageous.

By having the mercury-chamber divided into two parts—one communicating with the other, and one so arranged that the earth shall not be in contact with the mercury therein—I 95 can prevent the mercury from banking up in front of the conveyer at the tail end, as the mercury can escape from one part of the chamber to the other, and hence it can be prevented from being carried up the incline at 100 the end and lost with the refuse.

By examining Fig. 3 it will be seen that the ore is prevented from lying stationary to the right and to the left of the bottom central line of the conveyer, the cylinder or shell 105 above (if the ore-holder) the mercury-holder being outside and independent of the bottom walls of the cylinders by the sides of the opening. These walls converge downwardly, and the lower parts partially support the ore and 110 assist the conveyer-blades in thoroughly rolling and turning the dry material, and, at the same time, in order to reach the entire body of ore, it is not necessary to have the main body of the mercury disturbed by the conveyer-blades.

By the processes heretofore followed, in the carrying out of which use was made of conveyers, the greater part of the body of mercury was disturbed, or if this was avoided 115 there was a very imperfect advancing of the dry material upon the surface.

One of my aims is to accomplish the thorough agitation of the dry material with as little agitation as possible of the mercury. I 120 prefer to carry out my process by means of a mechanism in which the mercury-holder is

constructed and arranged, substantially as set forth, to have the upper surface of the mercury wider than the opening or passage between the downwardly-converging walls below the conveyer, as these walls assist in attaining the end above alluded to—to wit, rolling and agitating the ore—and this arrangement provides a recoil-chamber, into which the mercury can readily pass, to prevent its banking in front of the conveyer-blades, which I prefer to have merely dip through the very surface, but not pass down into the main body thereof.

In carrying out my process there is no disturbing the body of the mercury, the contact therewith of the extreme edge of the conveyer-blades being only sufficient to assist in disposing of the amalgam as it is formed.

It is a well-known fact in this art that the amalgamating processes heretofore followed cannot be applied to the treatment of a vast amount of material which is known to contain valuable metal, for the reason that the loss of the mercury (first through its amalgamating with the metallic parts of the machinery, and, secondly, from its being carried out of the apparatus on account of the great agitation and disturbance to which it is subjected) more than compensates for the gold which is obtained. I have succeeded in overcoming this difficulty by employing a conveyer of iron and treating the material in such way that the ore shall be rolled over and over while the main body of the mercury is, as above said, left undisturbed, I thus avoid the carrying of any part thereof out with the refuse.

Although I have herein most frequently made mention of the separation of gold from earth or refuse, &c., yet it will be, of course, understood that I do not limit myself to treating that metal only, as the process can be applied in obtaining any of the metals which are obtained by amalgamating.

Some of the advantages of the process can be obtained if the material be advanced otherwise than by the spiral conveyer-blades shown.

I do not herein claim the novel features incident to the mechanism which I have shown, preferring to claim those in another applica-

tion, No. 180,855, filed October 24, 1883, and herein claim only the process which I have devised. The mechanism shown is not limited to the process which I have herein claimed, as others can be carried out by means thereof— 55 as, for instance, the common one employing water for dissolving or suspending the earth.

What I claim is—

1. The herein-described improvement in the art of separating metal from earth or refuse, consisting in moving a mass of ore or refuse in a dry state over a mass of mercury by an iron conveyer, rolling said ore or refuse on lines oblique to the path of advance, and preserving the main body of the mercury in 65 an undisturbed state, substantially as set forth.

2. The herein-described improvement in the art of separating gold from refuse or earth, consisting in moving a mass of ore or refuse in a dry state over an elongated mass of mercury, the ore or refuse being caused to roll while partly supported by stationary walls and partly supported by the mercury, the main body of the latter being kept in an undisturbed condition, substantially as set forth. 70

3. The herein-described improvement in the art of separating gold from earth or refuse, which consists in rolling a mass of the earth and gold mingled together in a dry state over a body of mercury of gradually-increasing 80 depth by a conveyer, substantially as set forth.

4. The herein-described improvement in the art of separating gold from earth or refuse, which consists in moving a mass of mingled material over a body of mercury by means 85 acting positively and independently of the movements of the mercury, and causing said mercury, while the solid material is upon its surface, to flow in a current in the direction of the advance of the solid material, and withdrawing the amalgamated portion from the machine before it can be returned to the feeding end, substantially as set forth.

In testimony whereof I affix my signature in presence of two witnesses.
